UNITED STATES PATENT OFFICE.

EDWARD POSSON, OF CHICAGO, ILLINOIS, ASSIGNOR TO FAY E. POSSON, OF PARK RIDGE, ILLINOIS.

PARCEL-RACK.

1,105,830.

Specification of Letters Patent.

Patented Aug. 4, 1914.

Application filed December 26, 1913. Serial No. 808,859.

To all whom it may concern:

Be it known that I, EDWARD POSSON, a citizen of the United States, residing at Chicago, in the county of Cook and State 5 of Illinois, have invented certain new and useful Improvements in Parcel-Racks, of which the following is a specification.

My invention relates to parcel racks, and the principal object of the invention is to 10 provide a parcel rack to be placed above the seats of a railway car, or in other analogous situations, which will be so constructed as to inclose or partially inclose, the valises or other parcels which it holds 15 or supports so as to effectually prevent them from accidentally falling or being thrown from the rack.

The parcel racks ordinarily employed in railway cars are simply shelves or ledges 20 and it has not infrequently happened that suit cases and other like parcels have been dislodged from these racks by the vibration or swaying movement of the car, for example, and have fallen down upon the passengers, causing more or less serious injuries 25 for which the railroad companies have been held responsible.

The invention has for a further object to provide a novel and improved form of parcel rack which, besides securely engaging 30 and holding the parcels from accidental dislodgment, will be simple, compact and strong, inexpensive to manufacture and of slight appearance.

The invention has for further objects such 35 other new and improved constructions, arrangements and devices relating to parcel racks as will be hereinafter described and claimed.

The invention is illustrated, in certain preferred embodiments, in the accompanying drawings wherein—

Figure 1 is an end elevation of one form of the invention; Fig. 2, a front view of the 45 same showing one of the sliding gates in its open position; Fig. 3, a view similar to Fig. 2 but showing both gates closed; Fig. 4, a sectional view, taken on line 4—4 of Fig. 3; Fig. 5, a detail view of one of the 50 cross pieces of the slatted shelf structure; Fig. 6, a detail view of one of the adjustable hangers for supporting the upper guide rod for the gates; Figs. 7 and 8, sectional views taken on lines 7—7 and 8—8, respectively, 55 of Fig. 6; Fig. 9, is a sectional view of the

end of one of the guide rods and associated parts; Fig. 10, a front view of a modified construction; Fig. 11, a sectional view taken on line 11—11 of Fig. 10, and Fig. 12, an end elevation of the device shown in the 60 preceding two figures.

Like characters of reference designate like parts in the several figures of the drawings.

In the drawings, 25 designates the side 65 wall of a railway coach and 26 the deck of the same.

Referring first to Figs. 1 to 9 inclusive, the rack consists of a shelf and a pair of sliding gates, which latter are mounted on a 70 pair of guide rods, one of which is arranged at the forward edge of the shelf and the other adjustably supported from the deck of the car. The shelf, or rack proper, is shown as made up of a plurality of longitudinally extending rods or slats 27 connected 75 by cross pieces 28 which are supported on rods 29, 30 fixed in a pair of end brackets 31 secured to the side wall of the car and sustained at the middle by a similar bracket 80 32, the rods 27 passing through the center bracket 32 as shown in Fig. 4. The construction of the shelf might be modified without departing from my invention. In the construction shown, the bracket 32 is 85 formed with a perforated projection 33 supporting the lower guide rod 34 for the gates, the guide rod being preferably tubular with an interior thread at each end in order that it may be secured to projections 35 on the 90 end brackets 31 by means of screws 36 (Fig. 9). The upper guide rod 37, in this construction, is adjustably supported from the deck of the car by means of hangers 38 (Figs. 6, 7 and 8) having threaded stems 95 39 adapted to be received in socket members 40 affixed to the deck, the threaded stems 39 being engaged by adjusting nuts 41 arranged in recesses 42 formed in the socket members 40. The upper guide rod 100 37 is preferably tubular, and is secured to the hangers 38 by screws 36, 36^a like the screws fastening the lower guide rod to the end brackets, the screws 36^a extending through perforations 43 in the hangers. 105 The purpose of making the supporting devices for the upper guide rod adjustable is to adapt the rack to cars having roofs of different pitch.

Each rack is preferably provided with 110

two sliding gates 44, 45 consisting of longitudinally extending rods and end members to which the rods are secured, the end members of the gate 44 being designated 46 and those of gate 45 being designated 47. The end members are formed with perforations at opposite ends and the gates are loosely mounted on rods 34, 37. The members 46 are formed so that they extend out farther than the members 47 which permits the gate 44 to be moved to a position in front of gate 45, or the gate 45 to be pushed back of gate 44. As the rods 34, 37 are round so that the gates have a pivotal as well as a sliding relation therewith, the latter will accommodate themselves to different positions of the socket members 40 and different adjustments of the threaded hangers 38.

20 Operation: In order to place the suit case or other parcel A on the rack one of the gates is slid on the guide rods 34, 37 to a position in front of or behind the other, as the case may be. For example, the gate 45 may be pushed back of the gate 44, that is, from the position shown in Fig. 3 to that shown in Fig. 2. The parcel is then placed in the rack and the gate 45 moved back to its closing position. If the other end of the rack is to be used, gate 46 is manipulated in a similar manner. This form of rack, it will be observed, besides being constructed so as to prevent the parcels supported thereby from being accidentally dislodged, is very strong, the outer edge of the shelf being sustained by the gates and the devices for attaching the upper guide rod to the roof of the car.

40 The rack above described is what might be termed a two-unit rack, that is, it has two gates and may conveniently be arranged so that it will serve two seats. Obviously the same principles might be employed in the construction of a rack having a larger number of gates. The device might also be modified in other respects without departure from the principles of the invention. Therefore I do not wish to be understood as limiting the invention to the precise constructions, arrangements and devices shown except so far as said constructions, arrangements and devices are made specific limitations in certain of the claims herein.

55 A possible modification of the device is shown in Figs. 10 to 12 inclusive. In this construction the upper guide rod for the sliding gates, designated 48, 49, instead of being supported from the deck of the car is mounted upon projections 50 formed on the end brackets 51. In other details the construction of this rack may be the same as that of the rack previously described.

I claim:

65 1. In a parcel rack for railway cars and

the like, the combination with a supporting element, of a pair of retaining elements at the forward edge of the supporting element which are movable so that one may stand in front of the other, for the purpose described. 70

2. In a parcel rack for railway cars and the like, the combination with a supporting element, of a retaining element at the forward edge of the supporting element which is mounted so as to be slidable in the direction of its length. 75

3. In a parcel rack for railway cars and the like, the combination with a supporting element, of a pair of retaining elements at the forward edge of the supporting element which are slidable one over the other. 80

4. In a parcel rack for railway cars and the like, the combination with a shelf, of upper and lower guide rods arranged adjacent to the forward edge of the shelf, and a gate movably mounted on said guide rods. 85

5. In a parcel rack for railway cars and the like, the combination with a shelf, of upper and lower guide rods arranged adjacent to the forward edge of the shelf, and a pair of gates slidably mounted on said guide rods and constructed so that they may be moved to positions one in front of the other. 90

6. In a parcel rack for railway cars and the like, the combination with a shelf, of a retaining gate slidably mounted at the forward edge of said shelf. 95

7. In a parcel rack for railway cars and the like, the combination with a shelf, of a pair of retaining gates slidably mounted at the forward edge of the shelf and constructed so that they may be moved to positions one in front of the other. 100

8. In a parcel rack for railway cars and the like, the combination with a shelf, of upper and lower guide rods arranged adjacent to the forward edge of said shelf, a gate slidably and pivotally mounted on said guide rods, and means for adjusting the position of the upper guide rod. 105

9. In a parcel rack for railway cars and the like, the combination with a shelf, of upper and lower guide rods arranged adjacent to the forward edge of said shelf, a pair of gates slidably and pivotally mounted on said guide rods and constructed so that they may be moved to positions one in front of the other, and means for adjusting the position of the upper guide rod. 115

10. In a parcel rack for railway cars and the like, the combination with a shelf structure, of end brackets for the same, a guide rod secured between said brackets, a guide rod arranged above the aforesaid guide rod, and a pair of gates slidably mounted on said guide rods and formed so that they may be moved to positions one in front of the other. 125

11. In a parcel rack for railway cars and the like, the combination with a shelf struc- 130

ture, of end brackets for the same, a guide rod secured between said brackets, a guide rod arranged above the aforesaid guide rod, a pair of gates slidably and pivotally mounted on said guide rods and formed so that they may be moved to positions one in front of the other, and means for adjustably sustaining the upper guide rod.

12. In a parcel rack for railway cars and the like, the combination with a shelf structure, of end brackets for the same, a guide rod secured between said brackets, a guide rod arranged above the aforesaid guide rod, a pair of gates slidably and pivotally mounted on said guide rods and formed so that they may be moved to positions one in front of the other, hangers for the upper guide rods having threaded stems, socket members to receive said stems, and adjusting nuts on said socket members to engage said stems.

13. The combination with a parcel rack, of means for securing the same to the side wall of a railway car or the like, and ad-

justable means adapted to support the outer edge of the rack from the deck of the car.

14. The combination with a parcel rack, of means for securing the same to the side wall of a railway car or the like, adjustable means adapted to support the outer edge of the rack from the deck of the car comprising socket members, hangers having threaded stems, and adjusting nuts in said socket members to engage the threaded stems of the hangers.

15. In a parcel rack for railway cars and the like, the combination with a shelf structure, of end brackets supporting the same, upper and lower guide rods fixed to said end brackets, and a pair of gates slidably mounted on said guide rods and constructed so that they may be moved to positions one in front of the other.

Correction in Letters Patent No. 1,105,830.

It is hereby certified that in Letters Patent No. 1,105,830, granted August 4, 1914, upon the application of Edward Posson, of Chicago, Illinois, for an improvement in "Parcel-Racks," an error appears in the printed specification requiring correction as follows: Page 1, line 102, strike out the reference-numeral and comma "36,"; and that the said Letters Patent should be read with this correction therein that the same may conform to the record of the case in the Patent Office.

Signed and sealed this 1st day of September, A. D., 1914.

[SEAL.]

R. F. WHITEHEAD,
Acting Commissioner of Patents.
